UNITED STATES PATENT OFFICE.

WILLIAM H. FAUBER, OF CHICAGO, ILLINOIS.

DESIGN FOR A FORK-TUBE FOR BICYCLES, &c.

SPECIFICATION forming part of Design No. 30,243, dated February 21, 1899.

Application filed November 12, 1898. Serial No. 696,306. Term of patent 7 years.

To all whom it may concern:

Be it known that I, WILLIAM H. FAUBER, a citizen of the United States, residing in the city of Chicago, county of Cook, and State of Illinois, have invented and produced a new and original Design for Fork-Tubes Used in Bicycles or other Tubular Frames, of which the following is a specification, reference being had to the accompanying drawings, forming a part thereof.

In the said drawings, Figure 1 is a perspective view of a fork-tube embodying my design. Fig. 2 is a plan view thereof. Fig. 3 is a cross-section through the offset part of the tube, taken on line 3 3 of Fig. 2.

A fork-tube embodying my novel design consists generally of a tube having a straight part A and an offset part A', which is joined to the straight part by reversed or opposite bends a a'. The bend a', adjacent to the offset part A', is an abrupt or right-angled bend, while the bend a, adjacent to the straight or main part A, is of curved form approximating the arc of a circle. The offset part A' is flattened or provided with a flat outer face a², located in a plane at right angles with a plane passing through the curved and straight parts of the tubes, and the curved part a a is also provided with a flattened surface a³ on its in-

ner or convex face. Such flattened face extends from the curved part along the main portion A of the fork-arm to within a short distance of the extreme end thereof, which latter is of approximately circular form in cross-section. The flattened surfaces a² a³ meet each other at approximately right angles at the bend a', forming a straight line or angle at this point, which reaches nearly to the side faces of the tube, the angles at the side margins of the flat surfaces being slightly rounded. The surfaces of the offset part A' and of the curved part a opposite the flat surfaces referred to are rounded or made of approximately semicircular shape, as clearly seen in sectional view in Fig. 3. The said semicircular or convex faces of the offset part A' and curved part a are arranged to meet each other at an angle, as clearly shown in the drawings.

I claim as my design—

The design for a fork-tube for velocipedes and the like, substantially as shown and described.

WILLIAM H. FAUBER.
